UNITED STATES PATENT OFFICE.

OTTMAR A. GATRELL, OF COLUMBUS, OHIO, ASSIGNOR OF TWO-THIRDS
TO EDWARD B. HARANG AND LEONARD F. BENCKENSTEIN, OF SAME
PLACE.

VOTING-MACHINE.

SPECIFICATION forming part of Letters Patent No. 658,771, dated October 2, 1900.

Application filed July 29, 1899. Renewed April 12, 1900. Serial No. 12,633. (No model.)

To all whom it may concern:

Be it known that I, OTTMAR A. GATRELL, a citizen of the United States, residing at Columbus, in the county of Franklin and State 5 of Ohio, have invented certain new and useful Improvements in Voting-Machines; and I do hereby declare the following to be a full, clear, and exact description of the invention, such as will enable others skilled in the art 10 to which it appertains to make and use the same.

The object of my present invention is to provide an improved voting-machine in which the parts are of simple, economical, and durable construction, easily assembled, and reliable in operation.

My invention consists of the constructions and combinations of parts hereinafter described and claimed.

20 In the accompanying drawings, in which I have shown an embodiment of my improvements, Figure 1 is a front view with the upper right-hand corner and the top casing broken out, showing some of the interior construction and arrangement. Fig. 2 is a side elevation, parts being broken out to show the interior construction. In this view two keys are shown, one of which is pushed in. Fig. 3 is a top plan view, partially in horizontal 25 section, to show the interior mechanism. Fig. 4 is a detail view in side elevation, on a large scale, showing a push-key, its operating, locking, and releasing mechanism. Fig. 5 is a top plan view of the same. Fig. 6 is a 30 perspective view of a key-bar and the locking and releasing mechanism. Fig. 7 is a side view of a tape-operating key. Fig. 8 is a sectional view, on a large scale, taken through the front wall of machine and showing the 35 slotted register-guards.

Like characters of reference in the several views designate corresponding parts.

1 designates the frame or case of the machine. Arranged in vertical rows in the case 45 are push-key bars 2, having their outer ends, which protrude through holes in the front of the casing, provided with push-buttons and with springs to hold the keys normally withdrawn. The vertical rows of these keys are 50 designed for the nominees of different political parties, and they are so arranged that the

various nominees of the different parties for the same office occur in the same horizontal row. The inner ends of the keys are supported upon and pass through the rear wall 55 of an angle or channel bar 3, supported horizontally between the side walls of the casing. The key-bars 2 are formed in their upper sides at their inner ends with notches 2^a and 2^b and are provided at their under sides with 60 a wedge-shape projection 2^c, for the purpose hereinafter explained. Hinged upon a shaft 4, extending horizontally between the sides of the machine, is a flat bar 4^a, having pins 4^b. The bar 4^a hangs opposite the inner ends 65 of each of the horizontal rows of keys 2, so that when any key is pushed in the said bar is pushed rearwardly. Pivoted on the rear wall of the channel-bars 3, so as to swing in a plane parallel to said wall, are latches 3^a. 70 These latches are so arranged that they are supported by the pins 4^b when the bar 4^a hangs down and so that they drop into the notch 2^a of the key pushed in and into the notch 2^b of the keys not pushed in. When a 75 key has been pushed in, the engagement of the latch with the notch 2^a prevents any further movement of said key either inward or outward until the machine is reset for voting, and when the latch has dropped into the 80 notch 2^b the key cannot be pushed in until the machine is reset.

In order to prevent the pushing in of more than one key in any horizontal row, I arrange in the channel of the bar 3 a series of 85 horizontally-movable blocks 5, having their adjoining ends beveled, as indicated in Fig. 5. These blocks are yieldingly held together by springs 5^a, located between the end blocks and the casing, (see Fig. 3,) and the blocks 90 are so placed that the spaces between them are opposite the wedge projections 2^c on the push-keys 2, and when a key-bar is pushed in the blocks separate and allow the key to move through to operate the latch-releasing 95 bar 4^a; but the blocks in the channel are of such length and number that one key only can be pushed through to operate either the latch-releaser 4^a or the register hereinafter referred to.

To reset the machine, I arrange between the hinged bars 4^a and the channeled bars 3

- a frame composed of vertical strips 6 and a horizontal strip 6^a, uniting the upper ends of strips 6, and on the vertical strips 6 are pins 6^b to project under each of the latches 3^a.
- 5 The frame 6 6^a is arranged to be moved vertically; but it is normally depressed by coil-springs 6^d, between it and the top of the casting, so that pins 6^b shall not interfere with the operation of the latches 3^a when dropped 10 to lock the keys; but when the machine is to be reset the frame 6 6^a may be raised by the operation of the cords 6^c, passed through the top of the machine to lift the latches 3^a out of the notches in the key-bars, and when a 15 latch is lifted from a notch 2^a of a key pushed in the spring on the outer end of the key retracts the key to its operative or voting position.
- Each of the key-bars is furnished at its upper side with a roller-stud 2^d, and journaled vertically in the frame adjacent each vertical row of keys is a tubular shaft 7, provided with fixed curved arms 7^a, arranged so that when the shaft 7 is rocked in one direction 25 they shall throw all the keys in a vertical row inward, and journaled on a fixed shaft 8, arranged horizontally in the upper part of the machine, are bell-crank levers 8^a, each having one arm protruding through a slot 1^a in 30 the front wall of the machine and provided with a handle and the other arm connected by a drag-link 8^b with a pin 8^c on the shaft 7. By pulling down on the protruding arm of a bell-crank lever 8^a all the keys in a vertical 35 row may be pushed in. This operation votes a straight ticket; but a straight ticket cannot be voted in any party if one or more keys in another party-row have been voted, because the locking out of any of the keys prevents 40 the operation of the straight-ticket shaft 7.
- Each of the push-keys 2 is furnished with a pawl 2^e to operate a register of any suitable kind, the figures on said registers being preferably visible through slots 11^a in curved 45 strips 11, extending across the front of the machine, as indicated in Figs. 1 and 8.
- The names of the several party nominees are printed on strips of paper 9 held behind glass plates 10, secured between the vertical 50 rows of keys, the paper obscuring the register until removed by proper authority.
- In the right-hand part of the machine I have shown provision for voting for persons whose names are not printed on the regular 55 tickets. For each office there is a key and apparatus like that indicated in Fig. 7. The body of the key is substantially like that and wedge projection 2^e; but the front part designated 2, it also having notches 2^a and 2^b 60 of the key-bar is formed with an arched portion 2^f, having pawls for engaging a ratchet 12^a on the head of a paper-winding spool 12. The pawls in the arched portions act on the 65 said ratchet when the key-bar is retracted, while the pawls in the bar proper act on the ratchet when the key-bar is pushed. The

paper is wound from a spool 13, being passed around small rollers 14, journaled just above and below an opening in the front of the casting. When the voter wishes to vote for a 70 person whose name is not printed on any of the regular tickets, he writes the name through the slit. In order to prevent possible abuse of this privilege, the paper may be printed in black and white bars and the paper arranged 75 on the spools, so that when the key is out a black bar stands across the opening, and it is incumbent on the part of the voter to push in the key to bring down a white bar upon which the writing will be legible. When the machine is reset, the pawls in the upper part of the key bring down a black bar, so that each voter voting in this way is required to push in the key before he can vote for a person 80 not on any of the regular tickets.

In addition to registers for indicating the number of votes received by each nominee I provide a register of any approved form operated by the shaft at the top of the machine, from which the resetting-frame is operated 90 to indicate the number of voters voting at any election. The operation of this shaft may also effect the operation of a bell, as indicated at the left-hand side of Fig. 1. Both the register and bell may be inclosed in suitable casings, as indicated in Fig. 1.

What I claim, and desire to secure by Letters Patent, is—

1. In a voting-machine, a series of push-keys arranged in horizontal and vertical rows 100 each having two notches and a wedge-shaped projection, the angle-bar 3, the movable blocks 5 supported on the angle-bar and operated by the wedge-shaped projections, and the pivoted latches 3^a to transversely engage 105 notches, with means for holding all the latches 3^a of each horizontal row disengaged until operated by a key, substantially as described.
2. In a voting-machine, a series of push-keys arranged in horizontal and vertical rows 110 each having two notches, latches pivoted to swing transversely into said notches, a movable plate 4^a for each horizontal row carrying pins 4^b to hold said latches disengaged from said notches until pushed by one of said keys, 115 substantially as described.
3. In a voting-machine, a series of push-keys arranged in horizontal and vertical rows 120 each having two notches and latches pivoted to swing transversely into said notches, a 120 movable plate carrying pins for each horizontal row to hold said latches disengaged from said notches until pushed by one of said keys, and means for simultaneously disengaging said latches from the notches, substantially 125 as described.

4. In a voting-machine, a series of notched push-keys arranged in horizontal and vertical rows, latches pivoted to swing transversely into said notches, a movable plate 4^a for each 130 horizontal row carrying pins 4^b to hold said latches disengaged from said notches until

pushed by one of said keys, substantially as described.

5. In a voting-machine, paper-rolls 12 and 13, one of said paper-rolls having a ratcheted head, a spring-actuated key-bar having a two-part frame with reversely-acting pawls to engage said ratchet whereby paper may be wound from one roll to the other on both in-

ner and outer movement of the key, as shown and described. 10

In testimony whereof I affix my signature in presence of two witnesses.

OTTMAR A. GATRELL.
